UNITED STATES PATENT OFFICE

148,937

DESIGN FOR A WHEEL COVER OR
SIMILAR ARTICLE

George Albert Lyon, Allenhurst, N. J.

Application March 30, 1946, Serial No. 123,098

Term of patent 14 years

(Cl. D14—30)

To all whom it may concern:

Be it known that I, George Albert Lyon, a citizen of the United States and a resident of the village of Allenhurst, in the county of Monmouth and State of New Jersey, have invented a new, original, and ornamental Design for a Wheel Cover or Similar Article, of which the following is a specification, reference being had to the accompanying drawing, forming a part thereof.

On the drawing:

Figure 1 is a front view of a wheel cover showing my new design;

Figure 2 is a profile view showing in outline form the general cross-sectional contour of the cover.

In both figures the dotted lines illustrate a wheel with which the cover cooperates and show the relation of the cover to the wheel.

I claim:

The ornamental design for a wheel cover or similar article, as shown and described.

GEORGE ALBERT LYON.
